ENGLAND.

PROCESS FOR SEPARATING SODIUM CHLORID FROM LIQUORS CONTAINING IT AND SODIUM NITRATE IN SOLUTION.

1,230,162.

Specification of Letters Patent. Patented June 19, 1917.

Application filed May 20, 1915. Serial No. 29,443.

To all whom it may concern:

Be it known that we, ISIDORE BERKWOOD HOBSBAWM, a subject of the King of Great Britain and Ireland, residing in London, 5 England, and JAMES LOUIS GRIGIONI, a subject of the King of Great Britain and Ireland, residing in Richmond, Surrey, England, have invented a new and useful Improved Process for Separating Sodium 10 Chlorid from Liquors Containing It and Sodium Nitrate in Solution, of which the following is a specification.

This invention has reference to an improved process for separating sodium chlorid from liquors containing it and sodium nitrate in solution, and an apparatus therefor.

The liquors or solutions which we have more particularly in mind are those obtained by the action of water on caliches, 20 costras or any other form of naturally occurring sodium nitrate and sodium chlorid containing substances as well as the ripios or refuse dumpings from old or present nitrate workings.

In the present state of development of the extraction of these naturally occurring sodium nitrate and sodium chlorid containing substances it is found more economical not 30 to work to the fully concentrated liquor in the lixiviation plant, but to work to a weaker liquor than formerly and subsequently to concentrate by evaporation.

These liquors have hitherto been brought 35 up to full crystallizing strength on a commercial scale by concentrating to the convenient density, at which point the salt is rendered partially insoluble. This density can be considered purely empirical and depends entirely on local conditions and not 40 at all on the ultimate chemical composition of the liquor.

For this reason the sodium chlorid remaining in solution becomes a variable quantity. The liquors with the salt in suspension are subsequently run off into settling tanks wherein the bulk of the sodium chlorid is allowed to settle to the bottom by the dual agency of gravity and the cooling of 45 the liquor. The supernatant liquor is then decanted off into crystallization tanks in which by further cooling of the liquor the sodium nitrate is crystallized.

Such a method of dealing with the liquor

is altogether unsatisfactory for the following among other reasons:

(1) The supernatant liquor which is run off into the crystallization tanks usually contains a fairly considerable and always indefinite percentage of the sodium chlorid 60 in solution.

(2) Owing to the slowness of the deposition of the sodium chlorid in the settling tanks and further also owing to the fact that the temperature of the liquor while in said 65 tanks is substantially reduced, an unduly large percentage of the nitrate of soda crystallizes and settles with the sodium chlorid; and

(3) The process is not continuous. 70

It has also been known for many years that by merely boiling a liquor containing sodium nitrate and sodium chlorid some of the latter will be precipitated. The difficulty however which has existed was how to 75 effect the precipitation and separation of all the sodium chlorid by boiling the liquor without at the same time causing the deposition of sodium nitrate.

The main objects of our invention are (1) 80 to effect the separation of substantially the whole of the sodium chlorid from the liquor; (2) to obtain the sodium chlorid practically free from sodium nitrate; and (3) to effect the removal of the sodium chlorid without 85 any fall in temperature of the liquor.

We have found that by concentrating a liquor containing pure sodium nitrate and pure sodium chlorid in solution up to such a point that the temperature registered at 90 normal pressure *i. e.* at a pressure of 14.7 lbs. absolute per square inch, is 123° C. practically the whole of the sodium chlorid has been rendered insoluble without incurring the deposition of sodium nitrate. 95

This boiling point naturally varies according to the influence of other salts in the solution but in a pure solution of the two above mentioned salts irrespective of the quantities of either to begin with, this definite temperature at which the insolubilization of the one (sodium chlorid) is complete we have designated the critical temperature.

For the attainment therefore of the said objects our process consists in raising the 100 temperature of and concentrating liquor containing both sodium nitrate and sodium chlorid in solution, until the concentration

has been carried to such a degree that the boiling point of the liquor at normal or atmospheric pressure *i. e.* at a pressure of 14.7 lbs. absolute per square inch is about 123⁵ or 124° C. (more or less) and then maintaining the concentrated liquor at that temperature. At this temperature and pressure it will be found that sodium chlorid is rendered practically insoluble in a nitrate containing solution, and the liquor must be maintained at this temperature while the sodium chlorid is settling. The sodium chlorid is then removed by any suitable means from the desalted liquor or alternatively the desalted nitrate containing liquor may be removed, say through a filter. The sodium chlorid is then washed with hot water or steam to remove the nitrate containing liquor adhering to it.

10 The actual temperature to which any particular liquor should be raised in order to effect the precipitation of all the sodium chlorid without incurring deposition of sodium nitrate cannot be stated off-hand as this will vary slightly with different types of liquor. For example we have found when carrying on our experiments—the liquor being at normal or atmospheric pressure *i. e.* 14.7 lbs. absolute per square inch—

25 that with one type of liquor the critical temperature was 122° C. and with another 120° C. this variation as already mentioned being caused by the presence of soluble salts other than sodium chlorid and sodium nitrate.

30 The critical temperature of any particular liquor is determined experimentally on a sample of the liquor about to be treated on a commercial scale. Such a test is easily and quickly performed in the laboratory in the usual manner that is to say:—

40 The chemist determines the maximum boiling point at a pressure of 14.7 lbs. per square inch on a sample of the liquor and after freeing said liquor from the solids which have been deposited during the concentration, determines the absolute boiling point afresh and this is the critical temperature.

45 When the process is carried out at altitudes above sea level, in order to attain the critical temperature the apparatus is arranged to work at a back pressure sufficient to raise the pressure to 14.7 lbs. absolute per square inch.

50 Care must be exercised that when the liquor has been raised to the critical temperature it shall be maintained at that temperature for a time sufficient to allow the sodium chlorid to settle. If the liquor however is not raised in temperature to the critical point some of the sodium chlorid will be lost as it will remain in solution.

55 By means of our improved process above described the use of settling tanks heretofore essential, where evaporation is used, is

obviated and, further, inasmuch as the sodium chlorid is by our process recovered while the liquor is still at its maximum temperature the nitrate impurity in the salt is no more than that contained in the liquor naturally adhering to the crystals, and this may be subsequently removed from the salt by washing.

60 Our improved process may be carried out intermittently, that is to say, when one charge or volume of liquor has been treated as described, the vessel wherein the concentration and desalting were effected will be completely emptied and a fresh charge put in for treatment in a similar manner. It is however of considerable practical advantage to work the process continuously so that a substantially constant flow of liquor to be treated is maintained.

65 The accompanying drawing shows diagrammatically and merely by way of example one form of apparatus whereby our process may be so carried on continuously.

In said drawing the numeral 1 indicates the calandria of an evaporator and 2 a separator which is in connection with the calandria by pipes 3 and 4. The liquor is conveyed to the evaporator from a suitable source by a pipe 5 having a valve 6 by which the flow of liquor may be regulated or shut completely off. At the bottom of the separator is a filter box 7 having a filtering medium 8—for example wire gauze—a valve 9 enabling the filter box to be put into communication with the separator. 10 100 is a discharge pipe having a valve 11. The filter box is provided with a door 12 through which access may be had to remove the sodium chlorid therefrom.

A charge of liquor to be treated, having 105 been introduced through the pipe 5, is heated to its boiling point in the known manner by admitting live steam through the pipe 13. The liquor circulates in the direction of the arrows 14 and the vapor given off 110 may, if desired, be allowed to escape from the top of the separator to the atmosphere. The liquor is maintained at boiling point until—owing to the degree of concentration attained—its temperature is raised to 123 115 or 124° C. (more or less) which is the critical temperature at which substantially the whole of the sodium chlorid will have been rendered insoluble at a pressure of about 15 lbs. absolute per square inch.

120 When this critical temperature has been reached and the bulk of the sodium chlorid having settled, the attendant opens the valve 9 and allows a portion of the contents from the separator to flow or drop into the filter box 7 which is steam jacketed. The valve 9 is again closed and the valve 11 opened to permit the liquor from the filter chamber to flow off. This liquor is desalted nitrate containing liquor which may be run into 130

crystallization tanks or otherwise treated in any known manner to recover from it the sodium nitrate. The crystallized sodium chlorid which is retained in the filter box 5 by the filter medium 8 is next washed, for example by admitting steam or hot water to the upper part of the filter box—say through a pipe 20—and thereafter the door 12 is opened and the sodium chlorid removed. The hot water or condensed steam 10 used for washing the sodium chlorid may be transferred to storage tanks.

When the door 12 is again closed it will probably be possible to at once again open 15 the valve 9 for a further discharge from the separator 2 into the filter box and a repetition of the operations described.

The liquor to be treated flows continuously into the evaporator the valve 6 being 20 adjusted so that an average level is maintained, the level being of course highest at the moment when the valve 9 is about to be opened and lowest after the discharge into the filter box has taken place.

25 The live steam inlet pipe 13 has a valve 19 and the condensed steam outlet pipe 15 has a valve 16 by the adjustment of which valves the attendants may insure such a supply of steam that the liquor is maintained at the critical temperature notwithstanding that the volume of liquor in the evaporator is not constant.

30 The separator 2 is provided with an apron or shield 17 which will insure that the liquor entering the separator through the pipe 3, in its circulation through the separator, shall not pass directly back to the calandria 1 by the pipe 4 but shall first travel some distance down so as to permit the deposition 40 therefrom of the sodium chlorid held in suspension.

It is in practice preferable to heat the incoming liquor to some extent and for that purpose we provide a preliminary heater 45 18 which may be connected up with a live steam supply but for the sake of economy is preferably heated by the hot vapors from the separator 2 the said vapor passing through a pipe 21.

50 Further, it will be obvious that instead of

a single evaporator we may employ a multiple-effect evaporator this depending on the quantity of the water to be removed from the liquor to complete its concentration.

What we claim as our invention and desire to secure by Letters Patent is:—

1. An evaporation process for separating sodium chlorid from liquors containing it and sodium nitrate in solution, consisting in 60 concentrating and raising the temperature of the liquor to the point at which sodium chlorid is insoluble in the nitrate solution and maintaining the liquor at such temperature while the sodium chlorid is settling, which latter is then removed and washed. 65

2. An evaporation process for separating sodium chlorid from liquors containing it and sodium nitrate in solution, consisting in 70 concentrating and raising the temperature of the liquor to the point at which sodium chlorid is insoluble in the nitrate solution and maintaining the liquor at such temperature while the sodium chlorid is settling and thereafter filtering off the hot nitrate containing liquor without reducing its temperature. 75

3. A continuous process for desalting liquor containing sodium chlorid and sodium nitrate in solution, consisting in providing a constant flow of the liquor to be 80 desalted to an evaporator at a rate faster than that at which the evaporation therein is being effected—while maintaining the temperature of the liquor at a point at which sodium chlorid is insoluble in the solution— 85 so that a constant deposition of the sodium chlorid takes place and an average level of the liquor is maintained notwithstanding intermittent removal from the evaporator of the deposited sodium chlorid and of de-salted liquor. 90

In testimony whereof we have signed our names to this specification in the presence of two subscribing witnesses.
